SCALP STEAMER

Rex E. Davis, Anoka, Minn., assignor to The Charles Arnao Co. Inc., Minneapolis, Minn., a corporation of Minnesota

Application December 7, 1932, Serial No. 646,059

3 Claims. (Cl. 128—256)

This invention relates to steamers and particularly to steamers used in beauty parlors for scalp and hair treatments and is an improvement upon the apparatus disclosed in U. S. Letters Patent No. 1,421,756 issued on July 4th, 1922, to Charles C. Arnao.

At the present time steam treatments for the scalp are extensively employed in barber shops and beauty parlors for the thorough cleansing of the scalp and the treatment of unhealthy scalp and hair conditions, such as dandruff and falling hair. In carrying out the present methods, heated medicants, usually containing anti-septic liquids as well as oils are first applied and rubbed into the scalp. The scalp is then subjected to steam by the application of steaming towels or by treatment with the general type of steamer disclosed in the above identified patent. It is essential to continuously apply steam to the scalp to melt and thin the medicants and open the pores. Greatly improved results can be obtained if provision is made for massaging and manipulating the hair and scalp as the steam is being applied.

It is an object of my present invention to provide an improved and highly efficient apparatus adapted to uniformly effect the steaming of the human scalp and with which the scalp and hair may be manipulated and massaged during the steam treatment.

It is a further object to provide a steamer of the class described embodying a hood for loosely surrounding the scalp area of a human head and wherein any condensation of moisture any place within the interior of the hood will be collected and prevented from dropping from or coming in contact with the subject treated and will be returned to the steam generator.

A still further object is to provide an improved and simplified, compact and portable unit having provision for efficiently holding and heating ampules or containers for the ointments or medicants.

These and other objects and advantages of the invention will be more fully set forth in the following description made in connection with the accompanying drawing, in which like reference characters refer to similar parts throughout the several views, and in which:

Fig. 1 is a perspective view showing the preferred form of my scalp steamer;

Fig. 2 is a view showing the hood in vertical section and its connection with the generator;

Fig. 3 is a fragmentary rear view of the hood showing its attachment and support, and

Fig. 4 is a perspective view showing the manner in which the apertured portions of the hood are covered with a conventional bath towel and showing how the scalp and hair of the subject may be manipulated and massaged during the treatment.

The embodiment of my invention illustrated comprises a portable standard supported on a series of radially extending caster-equipped legs 5 and including a vertical tubular post 6 in which 65 is slidably and adjustably telescoped a supporting post 7. A suitable clamp 8 is provided for securing supporting post 7 in the desired elevated positions with reference to tubular post 6.

At the upper end of post 7 a suitable steam 70 generator is mounted enclosed within a cylindrical ornamental casing 9 and supplied with electrical heating elements serviced by the cord 10. Tumbler switches 11 mounted in the peripheral wall of casing 9 are conveniently disposed 75 for operation. A liquid container 12 is supported from casing 9 disposed conveniently at the rear of said casing and operates on the barometric seal principle to supply liquid through the tubular supporting conduit 12a to the tank 80 of the generator within casing 9.

The upper end of the cylindrical generator casing 9 is covered by a suitable closure cap 9a which carries an ampule holder 13 in the form of a centrally supported horizontal disk provided with a series of circumferentially arranged recesses for accommodating ampules or flasks C which contain medicants and oils to be used in the treatment.

The steam generator is provided at its upper end with a radially projecting discharge conduit 14 terminating in a triangular shaped supporting bracket 14a which has a flat outer surface.

My steaming hood, indicated as an entirety by the letter H is secured to and wholly supported by the bracket 14a and as shown is in the general form of an enlarged helmet symmetrically shaped and having an open bottom and front and constructed to loosely surround the scalp and hair of the person treated. The dimensions and shape of the hood are such that abundant space is left between the edge of the hood and a normal head to enable an operator's hands and arms to be thrust beneath the hood for massaging and manipulating the scalp and hair. Hood H has a symmetrical, rounded body positioned in such manner that a towel T or other flexible sheet may be draped about the top to snugly fit the contour thereof.

In the side portions of hood H and adjacent the rear of the hood elongated, kidney-shaped openings 15 are formed, oppositely arranged in such manner that an operator may stand behind the 5 apparatus and thrust both hands through the two openings to conveniently massage the scalp and hair at the rear of the head, or, if desired, an operator may stand at the side of the machine, as clearly shown in Fig. 3 and massage 10 the scalp by thrusting one of her arms through one of the apertures 15 and the other arm between the hood and the head of the subject.

Hood H may be constructed of any suitable rigid material and has a considerably thickened 15 triangular shaped attachment portion 16 at the rear end thereof which is adapted to be clamped tightly against the similarly shaped attachment bracket 14a. Screws 17 or the equivalent may be provided for securing the hood to said bracket. 20 It will be noted that a rectangular recess 16a is formed in the lower edge of the triangular thickened portion 16 of the hood which recess is aligned with the passage through conduit 14 but is, however, of less height than the internal diameter of the conduit. This recess in conjunction 25 with conduit 14 and an upturned flange afforded by the rim of the hood forms a diminished outlet for the steam from the generator and serves to direct the discharged steam upwardly against the 30 inner and rear wall of the hood.

The rim 18 referred to, as shown, is integrally constructed, covering the entire irregular lower edge of the hood proper and is secured thereto by suitable means such as the screws 19, see Fig. 35 1. The rim 18 has a continuous upturned lip or flange disposed at the inner edge of the hood and extending throughout its entire length. This lip or flange constitutes a moisture collection trough and is declined from the front or visor 40 portion of the hood to the connection of the hood at its rear with the bracket 14a in such manner that condensed moisture collected from all parts of the hood will be returned to the discharge conduit 14. The extreme rear portion of the 45 rim 18, at 18a underlies the recess 16a and cooperates with the thickened portion 16 at its lower edge and with the conduit 14 in forming a continuation of the steam discharge passage.

In use the contents of the ampules C are heated 50 by radiation from the top of the generator casing closure 9a as well as by convection currents of warm air passing upwardly through the generator casing through apertures 9b circumferentially arranged in the conical wall of the closure 55 cap.

In certain treatments the warm liquids from the ampules are rubbed into the scalp and hair of the subject preliminary to the steaming treatment. The head of the subject is then properly placed 60 beneath the hood H with the hood loosely surrounding the scalp area. The top and sides of the hood are then covered with a bath towel or other flexible sheet T, the rounded symmetrical contour and disposition of the hood being such 65 that the towel or sheet will remain in place nicely covering the apertures 15 to prevent escape of steam therefrom.

Steam is discharged through the diminished 70 passage 16a and is directed upwardly by the turned flange or lip at the rear of rim 18, the steam being deflected and diffused by the dome-like surface of the interior of the hood and being thus distributed and impinged against the hair and scalp and the entire area within the hood is permeated with steam which serves to open the pores

of the scalp and cleanse the skin and hair. Application of this steam thins the oil or other medicants applied to the hair and scalp, enabling the same to penetrate to the roots of the hair and enter the pores.

To facilitate the distribution of the medicants the operator may thrust her hands and arms through the massaging apertures 15 while the steaming treatment is being given and vigorously massage and manipulate the scalp and hair. The 80 kidney-shape of the apertures 15 provide the requisite freedom for massaging movement of the arms. Fig. 3 illustrates one manner in which the front and rear portions of the scalp may be massaged. It will be noted that the towel or sheet is not removed from the hood, the operator merely reaching under the edges of the towel and thrusting her arms through the apertures. It will also be seen that the entire back portion and crown of the scalp may be massaged through the two 85 massage apertures 15, the operator standing at the back of the device or that one of the sides and part of the front portion of the scalp may be massaged in the manner shown in Fig. 3 or, if desired, the operator may stand at the front of 90 the hood and massage the entire front portion of the scalp by inserting her hands and arms between the front of the hood and the scalp.

Because of the specific rounded or dome-like 95 contour of my hood, all moisture condensing therewithin will flow downwardly to the trough-like rim and will be collected and returned to the generator through the passage in the rear of the hood H and through the discharge conduit 14.

From the foregoing description it will be seen 100 that I have provided an improved, simplified and highly efficient portable scalp steamer adapted to be manufactured at relatively low cost. It will further be seen that with my apparatus provision is made for effectively massaging the scalp 105 while the steam is being applied, as well as for collection and removal of moisture condensed throughout the entire area of the inner wall of the hood.

It will, of course, be understood that various 110 changes may be made in the form, details, proportions and arrangement of the parts without departing from the scope of my invention, which, generally stated, consists in a device capable of carrying out the objects above set forth and in the 115 novel parts and combinations of parts disclosed and defined in the appended claims.

What is claimed is:—

1. A scalp steamer comprising a hood having an opening in the lower and forward portions thereof and adapted to loosely surround the scalp of a human head, said opening being defined by an irregular annular edge, the lowest point of said edge being disposed at the rear of said hood, a source of steam supply having its discharge in 130 communication with the interior of said hood and directed upwardly against said hood for deflection and distribution, a rim secured to the lower edge of said hood and having an up-turned inner flange throughout its length constituting a trough, the 135 inner contour of said hood being rounded whereby all moisture condensing against said hood will flow to and be collected by said trough, said rim being so arranged that collected moisture will be returned to the discharge of said source of steam 140 supply.

2. Apparatus for giving scalp steaming treatments comprising a hood shaped and adapted to surround in spaced relation the scalp portion of a human head, said hood having an open forward 145

- end and an open bottom, the openings being continuous, the rear of said hood forming on its interior a concave steam deflecting surface, a steam discharge nozzle mounted in the lower portion 5 of said hood adjacent the rear thereof, said hood having an elongated aperture in the rear portion thereof through which an arm of an operator may be thrust to massage the scalp and hair during the steam treatment.
- 10 3. Apparatus for giving scalp steaming treatments comprising a hood shaped and adapted to surround in spaced relation the scalp portion of a human head, said hood having an open for- ward end and an open bottom, the openings being continuous, the rear of said hood forming on its interior a concave steam deflecting surface, a steam discharge nozzle mounted in the lower portion of said hood adjacent the rear thereof, said 80 hood having a pair of oppositely disposed elongated apertures in the rear side portions thereof disposed respectively at the sides of the scalp of the subject treated and through which the arms of an operator may be thrust to enable the two 85 hands of the operator to cooperatively massage the scalp and hair during the steam treatment.
